ATTORNEY

UNITED STATES PATENT OFFICE.

JOHN MASTERS, OF LONDON, COUNTY OF MIDDLESEX, ENGLAND.

SCRATCH-BRUSH FOR THE USE OF JEWELERS AND OTHERS.

SPECIFICATION forming part of Letters Patent No. 359,733, dated March 22, 1887.

Application filed August 27, 1885. Serial No. 175,524. (No model.) Patented in England May 23, 1885, No. 6,503.

To all whom it may concern:

Be it known that I, JOHN MASTERS, of 175 Goswell Road, London, in the county of Middlesex, England, brush-manufacturer, have invented a new and useful Improvement in Scratch-Brushes for the Use of Jewelers and others, of which the following is a full, clear, and exact description.

My invention relates to improvements in the manufacture of what are known as "scratch-brushes," used by silversmiths, electroplaters, and gilders for preparing metal articles for electroplating; and the invention has particular reference to brushes of round or cylindrical form used for inside and outside work. Heretofore such brushes have been usually made by drawing the knots of wire into holes in a circular wooden stock, in consequence of which construction the wires forming the brush are almost devoid of elasticity, and, owing to the relatively considerable space occupied by the stock, it is impossible to make the brushes of less than a certain size.

Now, my invention has for its object such a method of constructing the brush that the wires forming the brush will have considerable elasticity, so as to yield to the inequalities of the work, will be securely fixed, and form a regular and even surface, owing to the stock or foundation being reduced to the smallest possible dimensions. The cost of manufacture is also considerably less than that of brushes as heretofore made, and they are more economical, as the wire can be worn down to the very center of the brush. These brushes can be made of sufficiently small diameter to be applied to the inside of the smallest articles, such as the mouth-pieces of musical in-

struments and other small apertures. The brushes can also be used for outside work. 40

The wire I employ for the brush part is the crimped or corrugated wire forming the subject of an application for British Letters Patent No. 5,752 of 1885.

In the accompanying drawings, Figure 1 is 45 a plan view of a brush made according to my invention; and Fig. 2 is a view, on an enlarged scale, of one of the corrugated wires used in carrying out my invention.

a is a fine wire, (preferably brass,) which is 50 crimped and corrugated, as shown in Fig. 2. This wire may be attached to the shaft or holder *b* in any well-known manner. The brush thus joined may be provided with any suitable handle.

The advantage of the crimped or corrugated wire is that the brush is fuller than a straight-wire brush containing the same quantity of wire bristles, and that crimped-wire bristles mutually support one another, and thus render the brush more elastic. 60

I do not claim brushes made of uncrimped or straight wire; but,

Having now fully described my invention, what I do claim is— 65

A brush made of corrugated or crimped wire, substantially as herein shown and described.

The above specification of my invention signed by me this 1st day of August, 1885.

JOHN MASTERS.
